John Judge, Seller patent

The schedule referred to, in these letters patent and making part of the same, containing a description in the words of the said John Judge himself of his improvement in the machine for sawing, dubbing or dressing ship timber.

Specification

The log, timber, plank, or other timber fastened to the carriage A A by means of the screws B B and advanced to the wheel C by means of a rack and pinion as applied to a saw mill carriage or by an endless chain passing over a ratchet or chain wheel, or by the chain two sets of carriages may be used which will keep the cutter wheel constantly employed. The cutter wheels may be made to suit any thickness of timber, by making them advance towards or recede from each other by means of a screw on the shaft or a groove and key in the same as wheels are generally hung on round shafts.

In this machine what I claim as my invention is the application of cutters on the periphery of wheels, to the sawing, dubbing or dressing of ship timber, planks, &c &c with the omission of fastening the timber &c to the carriage and also the manner of advancing the wheels.

The different thicknesses of leather &c
